UNITED STATES PATENT OFFICE.

WALTER E. SANDS, OF NEW YORK, N. Y., ASSIGNOR, BY MESNE ASSIGNMENTS, OF ONE-HALF TO JORDAN BROTHERS, OF NEW YORK, N. Y., A CORPORATION OF NEW YORK.

CIRCUIT-BREAKER.

1,069,815.

Specification of Letters Patent. Patented Aug. 12, 1913.

Application filed June 30, 1909. Serial No. 505,113.

To all whom it may concern:

Be it known that I, WALTER E. SANDS, a citizen of the United States, residing in the borough of Brooklyn, city of New York, county of Kings, State of New York, have invented a certain new and useful Circuit-Breaker, of which the following is a specification.

The object I have in view is to produce a circuit breaker which will be always inclosed whether in open or closed position, which cannot be tampered with, but which can be readily opened by one having authority, which will not be short circuited by water and will not be injured by fire. These and further objects will appear from the following specification and accompanying drawings, considered together or separately.

In the drawings: Figure 1 is a front elevation of a circuit breaker embodying my invention; Fig. 2 is a section on the line 2—2 of Fig. 1, showing the circuit breaker in closed position in solid lines and open position in dotted lines; Fig. 3 is a section on the line 3—3 of Figs. 1 and 2, showing the circuit breaker in closed position; and Fig. 4 is a view similar to Fig. 3 of a slightly modified form of device, showing the breaker in open position.

In all of the views like parts are designated by the same reference characters.

The apparatus comprises a box A of suitable material, such as sheet steel, having sides 1, 1, a top 2 and a bottom 3. According to one form of my invention, the box may have a back 4 (as shown in Fig. 3), but such back is not necessary and may be omitted (as shown in Fig. 4). The element 5 is hinged at 6 to the bottom of the box, and is secured in closed position by any suitable device, such as a padlock 7. It will appear from Fig. 2 that the element 5—when in closed position—is inclined and that the top 2 of the box is much longer than the bottom 3. The sides 1, 1 are formed to accommodate the inclined position of the element 5 and the longer top than bottom, so that a complete inclosure is produced. The forward portion of the top 2 is curved (as shown in Fig. 2). The box is provided with ears 8, by means of which it may be attached to the switchboard or other support. The operating portions of the switch are located within the box and comprise the contact members in the form of clips 9, which are fixed

to the back, and the contact members in the form of plates 10, 10. The plates 10, 10 are supported upon a movable member 11. This member 11 is hinged at 12 adjacent to the hinges 6 of the element 5. The movable member 11 is preferably made of sheet material, as shown, and is provided with flanges at top, bottom and sides. Said member, as is shown, is lined with a slab of slate or other suitable insulating material 13, to which the plates 10, 10 are secured. The clips 9, 9 are shown as in engagement with a slab 14 of suitable insulating material.

In the modification of the invention in which there is no back 4, the sides 1, 1 are flanged and engage with the slab 14,—thus closing in the back of the box. The swinging member 11 is adapted to be moved to open and close the breaker, such member swinging on the hinge 12. Any suitable means may be employed for swinging the member 11, but I have illustrated manual actuating means, such as a handle 15, secured to the arm. This handle may be grasped through an opening 16 formed in the element 5. The opening shown is rectangular and of considerable size. It is apparent that the size and shape of the opening may be modified without departing from the spirit of the invention.

The member 11 is provided with a staple 17, which is adapted to come in juxtaposition with a staple 18 on the element 5, and these two ears may be secured together by a padlock or other locking device (not shown). The two plates 10, 10 are connected together by a fuse 19 in the usual manner.

The switch may be opened by removing the padlock 7 and dropping the element 5. The member 11 can then be swung forward and dropped,—exposing the clips 9, 9, the plates 10, 10 and the fuse 19.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent, is:

1. A switch comprising a box, contact members supported therein, a movable mem-

ber carried by and snugly fitting the inside of said box, and contact members carried by said movable member and coöperating with said first named contact members.

5 2. A switch comprising a box having a cover with an opening therein, a pivoted member supported within said box and snugly fitting it and operated through the opening in said cover, and coöperating contact members carried by said box and by said pivoted member.

10 3. A switch comprising fixed contact members, movable contact members coöper-

ating therewith, a pivoted member on which said last named contact members are supported, and a box surrounding said parts and snugly engaging said pivoted member whereby the contact members are always inclosed whether the switch is open or closed.

15 This specification signed and witnessed 20 this 15th day of June, 1909.

WALTER E. SANDS.
